UNITED STATES PATENT OFFICE

166,723

SERVING KNIFE BLADE OR SIMILAR ARTICLE

John O. Van Koert, Newburyport, Mass., assignor to Towle Manufacturing Company, Newbury-port, Mass., a corporation of Massachusetts

Application August 23, 1950, Serial No. 11,888

Term of patent 14 years

(Cl. D22—3)

To all whom it may concern:

Be it known that I, John O. Van Koert, a citizen of the United States of America, residing at 309 Merrimac Street in Newburyport, county of Essex, and State of Massachusetts, have invented a new, original, and ornamental Design for Serving Knife Blade or Similar Article, of which the following is a specification, reference being had to the accompanying drawing, forming a part thereof.

Fig. 1 is a side elevational view of a serving knife blade or similar article, showing my new design;

Fig. 2 is a top plan view thereof;

Fig. 3 is an end elevational view thereof, as seen from the bolster end; and

Fig. 4 is a perspective view thereof.

The dominant features of my new design are shown in solid lines in the drawing, the broken line fragmentary showing of a representative handle being for illustrative purposes only.

I claim:

The ornamental design for a serving knife blade or similar article, substantially as shown and described.

JOHN O. VAN KOERT.
